(57) **CLAIM**

The ornamental design for a cabinet as shown and described.

DESCRIPTION

FIG. 1 is a front, top, and left perspective view of a first embodiment of a cabinet showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a rear, bottom, and right perspective view thereof;

FIG. 9 is a front, top, and left perspective view of a second embodiment of a cabinet showing my new design;

FIG. 10 is a front elevational view thereof;

FIG. 11 is a rear elevational view thereof;

FIG. 12 is a left side elevational view thereof;

FIG. 13 is a right side elevational view thereof;

FIG. 14 is a top plan view thereof;

FIG. 15 is a bottom plan view thereof;

FIG. 16 is a rear, bottom, and right perspective view thereof;

FIG. 17 is a front, top, and left perspective view of a third embodiment of a cabinet showing my new design;

FIG. 18 is a front elevational view thereof;

FIG. 19 is a rear elevational view thereof;

FIG. 20 is a left side elevational view thereof;

FIG. 21 is a right side elevational view thereof;

FIG. 22 is a top plan view thereof;

FIG. 23 is a bottom plan view thereof; and,

FIG. 24 is a rear, bottom, and right perspective view thereof.

The broken lines shown in the drawings represent portions of the cabinet that form no part of the claimed design.
